VANITY CASE

Benjamin Rosen and Albert Rosen, Seattle, Wash., assignors to Durabilt Luggage Manufacturing Company, Seattle, Wash.

Application February 18, 1957, Serial No. 44,898

Term of patent 7 years

(Cl. D86—10)

FIG. 1

The dominant feature of this design resides in the V-shaped ornamentations on the cover of the vanity case.

We claim:

The ornamental design for a vanity case, as shown and described.
